UNITED STATES PATENT OFFICE.

SAMUEL E. HORNE, OF TORONTO, ONTARIO, CANADA, ASSIGNOR OF THREE-FOURTHS TO LOUIS F. LAING, WILLIAM W. OGDEN, AND STEPHEN M. HAY, ALL OF SAME PLACE.

PRINTER'S GALLEY.

SPECIFICATION forming part of Letters Patent No. 423,559, dated March 18, 1890.

Application filed February 23, 1889. Serial No. 300,878. (No model.)

To all whom it may concern:

Be it known that I, SAMUEL E. HORNE, printer, of the city of Toronto, in the county of York, in the Province of Ontario, Canada, have invented a certain new and useful Improvement in Printers' Galleys, of which the following is a specification.

The object of the invention is to connect the side-stick to the galley in such a manner that it may be easily adjusted and fixed for the purpose of locking the type in the galley without using loose quoins, such as are now commonly employed; and it consists, essentially, in connecting the side-stick to the galley in such a manner that it may be laterally adjusted by the longitudinal movement of a bar provided with pins or projections designed to fit into slanting grooves formed in plates attached, respectively, to the side-stick and bottom of the galley, substantially as hereinafter more particularly explained.

Figure 1 is a perspective view of my improved galley with the side-stick in position. Fig. 2 is a similar view with the side-stick removed. Fig. 3 is a perspective bottom view of the side-stick and its attachments.

In the drawings, A is the galley of ordinary construction, but with a portion of one of its ends removed.

30 B is the side-stick, having a tongue a formed a tone end to fit into a groove b, made on one end of the galley A. The groove b is longer than the tongue a, so as to permit the stick B to be laterally adjusted for the purpose of locking the type in the galley or moving it to permit the type to be taken out of the galley. A hole d is made in the end of the side-stick B opposite to that on which the tongue a is formed. This hole d fits over

40 a pin e when the stick B is placed in the position indicated in Fig. 1. By thus connecting the side-stick B to the galley A the said side-stick may be easily removed from the galley or replaced in position, as required.

45 Two plates C are attached to the top of the side-stick B, and a plate D is also attached to the side-stick B, but on its bottom side and between the plates C. The bar E is provided with pins or projections F, which are 50 designed to fit into grooves or slots G, made in the plates C and D.

H represents plates fixed to the bottom of

the galley A. The plates H have grooves or slots I, into which the two end pins projecting from the bar E fit when the said side-stick is placed in its position, as indicated in Fig. 1. The grooves or slots I correspond with the grooves or slots G, except that they slant in the opposite direction. It follows, therefore, that when the side-stick, with its attachments, is placed in position in this galley A the longitudinal adjustment of the bar E causes a lateral movement of the side-stick B sufficient to accomplish the purpose for which the side-stick is employed. It will of course be understood that instead of the grooves or slots G and I the same effect would be produced by ribs, in which case grooved projections on the bar E would be employed instead of the pins F.

By connecting the side-stick to the galley in the manner I have described loose quoins are dispensed with, and the constant annoyance caused by the loss of the quoins and the difficulty in properly adjusting the side-stick while making corrections in the type are avoided. It will also be seen that the old style of galley can be readily altered to suit my invention, it being merely necessary to provide the plates and adjusting-bar.

What I claim as my invention is—

1. The side-stick B, having a tongue a to fit into the groove b, made in the end of the galley A, and a hole d to fit over the pin e, projecting from the opposite end of the said galley, and the plates C, fixed to the side-stick B and having grooves or slots G made in them, in combination with the bar E, provided with pins F to fit into the grooves or slots G and into grooves or slots I, substantially as and for the purpose specified.

2. The galley A, the side-stick B, having slotted plates C on its upper side near its opposite ends, a central slotted plate D on its under side, and the plates G H, attached to the galley and slotted in opposite directions to the slots in the plates C and D, in combination with a bar E, provided with pins F, fitting in said slots, substantially as described.

Toronto, February 14, 1889.

SAMUEL E. HORNE.

In presence of—

CHARLES C. BALDWIN,
W. G. MCMILLAN.
